DESIGN FOR A MOLDING OR SIMILAR ARTICLE

Joseph Ingrassia, Brooklyn, N. Y.

Application January 31, 1936, Serial No. 60,919

Term of patent 3½ years

To all whom it may concern:

Be it known that Joseph Ingrassia, a citizen of the United States, residing at Brooklyn, in the county of Kings and State of New York, has invented a new, original, and ornamental Design for a Molding or Similar Article, of which the following is a specification:

In the accompanying drawing forming a part of the application:—

Fig. 1 is a perspective view of a section of molding, which may be of indefinite length, showing my new design.

Fig. 2 is a bottom elevational view of Fig. 1.

One unit of the design is confined between dot and dash lines AA and BB. The units of the design repeat indefinitely.

I claim:—

The ornamental design for a molding or similar article, as shown and described.

In testimony whereof I affix my signature.

JOSEPH INGRASSIA.
